UNITED STATES PATENT OFFICE.

EUGENE L. MAUPAI, OF WEST NEW YORK, NEW JERSEY.

PROCESS OF DYEING RAW SILK.

1,332,675.

Specification of Letters Patent.

Patented Mar. 2, 1920.

No Drawing.

Application filed May 23, 1919. Serial No. 299,250.

To all whom it may concern:

Be it known that I, EUGENE L. MAUPAI, a citizen of the United States of America, residing at West New York, Hudson county, 5 State of New Jersey, have invented certain new and useful Improvements in Processes of Dyeing Raw Silk, of which the following is a full, clear, and exact description.

This invention relates to an improvement 10 in the process of dyeing raw silk. One of the objects of my invention is to dye single thread or grege silk, containing natural gum, while in the hank or warp.

So far as I am aware, the dyeing of 15 twisted silk containing natural gum while in the hank or warp has never been successfully accomplished, that is to say, dyed to produce a fast color, for the reason that the gum in the silk dissolved, causing the silk 20 or hank to become a compact mass which made the weaving or throwing thereof almost impossible.

To accomplish the result sought for, I 25 preserve the natural gum in the silk, so as to maintain the threads in the natural state until the dyeing operation has been completed. By preserving the gum I am able to prevent the mass of silk from becoming matted, which would prevent the ready separation of the strands or threads. To 30 preserve the gum I treat the silk so as to harden same to make it proof against dissolving during the operations prior to the final step which consists in removing the gum from 35 the dyed silk.

To accomplish the partial hardening of the gum in the silk, I subject the silk threads, while in the hank or warp, to an acid bath, such as sulfuric or hydrochloric 40 acid, diluted with warm water, the temperature of the water depending upon color requirements.

After the silk has been subjected to the 45 gum preserving or hardening step, I subject the same to the action of a solution of alum, or of chrome-acetate, or of chrome chlorid, or of nitrate of iron (or any iron-liquor used in dyeing), all depending upon the color to be used for dyeing. The action of these 50 mordanting or fixing elements is to still further harden the gum and will also produce an insulation around each thread, said insulation protecting the hardened gum in or on the threads against the action of the 55 alkali or acid present in the dyeing solution.

The threads which have been treated as

above described, will be pliable but firm and can be worked for a considerable length of time in the dyeing solution without affecting the ceraceous matter in the gum present 60 in the silk.

After the operation just described has been completed, the silk may be dyed in the usual manner. The dye employed will of course be such as has an affinity for the particular hardening fluid or preservative employed to produce the insulation hereinbefore set forth.

When the raw silk treated as described has been dried, after the dyeing operation, it 70 will be ready for weaving. After the weaving operation has been performed, the fabric will be boiled in a strong solution of soap and water, which will eliminate the gum or ceraceous matter and bring out the color and 75 luster in the fabric.

It will be apparent that I preserve the ceraceous matter or gum in the raw silk until after the dyeing and weaving operations, the removal of the gum being the final 80 operation. The retention of the gum maintains each thread in the hank an individual element, and hence they can be readily separated when they are to be woven or thrown. The dyeing operation is not in the least 85 hampered by the presence of the gum, as the dye will penetrate the gum, but will not soften or dissolve same, owing to the hardening process described. As the dye will penetrate and pass through the gum, the silk 90 fiber will be affected or dyed thereby.

One of the advantages of my improved process is that the threads comprising a hank of silk can be treated in untwisted condition in hanks or warps; or in other words, 95 the natural gum preserved or hardened in each thread composing the hank, thus enabling the storage of the hanks for dyeing at a future time. In other words, silk threads can be preserved for a considerable 100 length of time by subjecting same to the hardening step of my improved process. The dyeing operation does not necessarily have to immediately follow the hardening or insulation of the gum in or on the silk threads.

Having described my invention, what I claim is—

1. The process of dyeing untwisted silk threads consisting in hardening the natural gum or ceraceous matter therein contained, then dyeing the silk, and finally removing the gum or ceraceous matter.

2. The process of dyeing untwisted silk threads in the hanks, consisting in first subjecting the silk to a diluted acid bath to harden the natural gum or the like in or on the same, then mordanting the threads to render the gum resistant to the action of an acid and alkali, then dyeing the thus treated silk, and finally removing the gummy or ceraceous matter.
- 10 3. A step in the process of dyeing raw silk consisting in coating the strands thereof with an acid and alkali resisting element to protect the natural gum in or on said strands and dyeing the thus treated silk.
- 15 4. Subjecting raw silk threads to the action of diluted acid to harden the natural gum or the like in or on said threads, then coating the thus treated gum with an alkali and acid resisting element, then dyeing the 20 silk, then weaving the silk into a fabric, and finally removing the gum from the woven fabric.
5. Subjecting raw silk threads to the action of diluted acid to harden the natural 25 gum or the like in or on said threads, then coating the thus treated gum with an alkali and acid resisting element, then dyeing the silk, then weaving the silk into a fabric, then subjecting the woven fabric to the action of 30 a strong solution of soap and water to remove the gum therefrom.
6. A step in the process of dyeing raw silk, consisting in artificially hardening the natural gum in or on the silk by first treating the
- same with an acid bath, and then with mordanting elements.
7. A step in the process of dyeing raw silk, consisting in first treating the raw silk with a dilute acid hardening solution, and then with mordanting elements adapted to further harden the gum therein and to insulate the same against the action of acid and alkali contained in dyeing solutions.
8. The process of dyeing untwisted raw silk threads, consisting in first treating the 45 silk threads to preserve the natural gum or the like in or on the same, then dyeing the silk threads with the gum preservative thereon, and finally removing the gum after the silk threads have been dyed.
9. In the process of dyeing raw silk, the step consisting in subjecting the artificially hardened gum coating of the silk thread to the action of solution of chrome acetate to still further harden the gum and produce 50 more complete insulation around the thread.
10. In the process of dyeing raw silk, the step consisting in subjecting the artificially hardened gum coating of the silk thread to the action of a second hardening agent for 55 completing the hardening of the gum and the insulation of the thread.

Signed at New York city, N. Y., this 21 day of May, 1919.

EUGENE L. MAUPAI.
